(57) **CLAIM**

The ornamental design for a flexible conduit screw jay, as shown and described.

DESCRIPTION

FIG. 1 is a top view of a flexible conduit screw jay showing my new design;

FIG. 2 is a front view thereof;

FIG. 3 is a bottom view thereof;

FIG. 4 is a right side thereof;

FIG. 5 is a back view thereof;

FIG. 6 is a left view thereof;

FIG. 7 is a first isometric view thereof;

FIG. 8 is a second isometric view thereof;

FIG. 9 is a third isometric view thereof; and,

FIG. 10 is a fourth isometric view showing the screw jay screwed onto a metal stud with flexible conduit being retained by the screw jay.

The broken lines in FIG. 10 represent a metal stud, flexible conduit and a screw and are or are not part of the claimed design and are shown for the convenience of illustration.
